EARL S. MACPHERSON, OF DETROIT, MICHIGAN, ASSIGNOR TO HUPP MOTOR CAR CORP.,
OF DETROIT, MICHIGAN, A CORPORATION OF MICHIGAN

COOLING SYSTEM

Application filed June 7, 1928. Serial No. 114,308.

This invention relates to cooling systems for internal combustion engines and more particularly to improvements in the arrangement of the circulatory system therefor.

5 The invention contemplates a water pump mounted on the head of the engine, together with a thermostatic by-pass and means for conducting the water from the pump directly through a portion of the cylinder head in 10 contact with that portion of the wall of the combustion chamber most remote from the spark plugs.

With a cooling system arranged and constructed in accordance with this invention 15 certain noteworthy advantages in motor operation are obtained. For a given amount of heat absorbed by the water, the inlet and outlet temperatures will be substantially the same as with a conventional pump circulating 20 system, but inasmuch as the entering water passes through a part of the cylinder head before entering the cylinder jackets, the jacket temperature will be higher than with the conventional types of systems. Furthermore, 25 it has been ascertained that the temperature of that part of the combustion chamber most remote from the spark plug has a considerable influence upon the efficiency of the motor. If, for instance, the temperature 30 at that point is relatively high, detonation is present to a greater extent than when the temperature is relatively low. With a cooling system in accordance with the present invention the temperature at this point 35 will be lower than with conventional types of systems.

The invention contemplates other objects, advantages, and the novel details of construction, all of which will be made more apparent 40 as this description proceeds, especially when considered in connection with the accompanying drawings, wherein:—

Figure 1 is a fragmentary sectional view taken substantially on the plane indicated by line 1—1 in Figure 3;

Figure 2 is a fragmentary sectional view taken substantially on the plane indicated by line 2—2 in Figure 1;

Figure 3 is a fragmentary sectional view 50 through an internal combustion engine em-

bodying a cooling system in accordance with this invention; and

Figure 4 is a fragmentary horizontal sectional view taken substantially on the plane indicated by line 4—4 in Figure 3.

Referring now particularly to the drawings wherein like characters indicate like parts, it will be noted that there is illustrated an internal combustion engine 10 including a plurality of cylinders 11. The reference character 12 indicates generally the cylinder head in which is mounted the usual spark plugs 13, the reference character 14 indicating the usual valves for controlling the intake and exhaust from the combustion chamber 15 of the cylinders.

55 Mounted upon the head of the engine is a pump 16 for pumping or circulating the cooling water used in cooling the engine, this pump being illustrated as driven from the fan-shaft 17 of the fan 18.

That part of the circulatory system associated with the engine is connected to the lower opening of the radiator (not shown) by means of a conduit 19, the water flowing from this 60 conduit into a chamber 20 and thence into the intake side of the pump 16. The water is delivered by the pump into a longitudinally extending compartment or passageway 21 formed in the head 12 of the motor, this passageway 21 constituting a water inlet manifold. As seen from Figure 3 the inlet manifold 21 is divided from the remainder of the head 12 by means of a longitudinally extending wall 22. This manifold or passageway 65

21 connects by means of a plurality of openings 23 with that portion of the cylinder jackets 24 farthest from the valves 14. As the water passes downwardly into the cylinder jackets it is deflected by means of a baffle 25 arranged in the path thereof. This baffle 25 may be conveniently mounted upon a cover plate 26 adapted to close an opening 27 in the cylinder water jacket customarily used for inspection purposes.

95 The water entering the cylinder jackets through the openings 23 is deflected by the baffle 25 toward the valve side of the engine where it rises around the valve in the customary manner and up into the head proper. 100

From the head proper the water flows into a chamber 28 to which is connected a substantially tubular member 29 constituting a water outlet and thermostat cover. Mounted within the member 29 is a thermostat 30 adapted to control a double valve 31 provided with a peripherally arranged valve surface 32 and a substantially centrally arranged valve surface 33. The valve surface 32 is adapted to seat on the valve seat 34 formed on the lower end of the element 29, and when thus seated to intercept the passage of the water through the outlet element 29 which is connected to the upper end of the radiator (not shown). In its other position the valve is adapted to seat on the valve seat 35 of a by-pass opening 36 of a by-pass passageway or chamber 37 communicating with the chamber 20 and consequently with the pump 16. Hence, the thermostat under certain conditions, that is when the water is hot, seats the valve 31 upon the seat of the by-pass opening 35 and permits the water to flow through the outlet member 29 to the radiator. Under other conditions the by-pass is opened and the water is conducted directly back to the pump without flowing through the radiator.

It will be noted that as the water is discharged from the pump it is conducted directly into the water inlet manifold 21 which constitutes the wall of the combustion chamber most remote from the spark plugs 13. Thus, this portion of the wall of the combustion chamber is maintained at a lower temperature than would otherwise result with the resulting advantage that detonation is present to a smaller extent. Inasmuch as the cooling water is first caused to pass through this portion of the cylinder head and to contact with the adjacent portion of the wall of the combustion chamber and is subsequently conducted to the cylinder jackets, the jacket temperature will be relatively higher than with the conventional types of systems because of the heat absorbed by the water during its contact with the aforesaid portion of the cylinder head. This system of cooling and the resulting relative wall temperatures obtains certain advantages in motor operation by effecting the efficiency of the combustion.

While the invention has been described herein somewhat in detail and with particular reference to a definite arrangement and association of parts, nevertheless it will be apparent to those skilled in this art that the principles of this invention are capable of expression in other types of apparatus so that reservation is made to make such changes and rearrangement of parts as may come within the purview of the accompanying claims.

What I claim as my invention is:—

1. The combination with an internal combustion engine, of a cooling system therefor including, a water pump, means for initially conducting the cooling water therefrom

longitudinally through a portion of the cylinder head prior to entering the cylinder jackets and means for returning the water to the said pump through the cylinder head.

2. The combination with an internal combustion engine, of a cooling system including, a water pump, means for conducting the water from said pump longitudinally through a portion of the cylinder head, means for conducting the water from said head to the cylinder jackets, a chamber adjacent said pump, and means for conducting the water from said jackets through said head to said chamber.

3. The combination with an internal combustion engine including a cylinder block and a cylinder head, of a cooling system including, a water pump, a water inlet manifold in the head of the engine connected to receive the water from said pump, a cylinder water jacket connected to said manifold, said jacket being connected to the water chamber in the engine head proper, whereby water is circulated from said pump through said manifold, cylinder jackets and cylinder head proper in the sequence named.

4. The combination with an internal combustion engine including a cylinder block and a cylinder head, of a cooling system including, a water pump, a water inlet manifold in the head of the engine connected to receive the water from said pump, said manifold constituting a portion of the wall of the combustion chamber remote from the spark plug, a cylinder water jacket connected to said manifold, said jacket being connected to the water chamber in the engine head proper, whereby water is circulated from said pump through said manifold, cylinder jackets and cylinder head proper in the sequence named. 100

5. The combination with an internal combustion engine including a cylinder block and a cylinder head, of a cooling system therefor including, a pump mounted on the head of the engine, an intake manifold formed in said head to receive the water discharged from said pump, means for conducting the water from said manifold to the cylinder jackets and from the cylinder jackets to the head proper and thence to said pump. 105

6. The combination with an internal combustion engine including a cylinder block and a cylinder head, of a cooling system therefor including, a pump mounted on the head of the engine, an intake manifold formed in said head to receive the water discharged from said pump, said manifold being arranged adjacent that portion of the combustion chamber farthest from the spark plugs, means for conducting the water from said manifold to the cylinder jackets and from the cylinder jackets to the head proper and thence to said pump. 110

7. The combination with an internal combustion engine, of a cooling system therefor

including, a pump, means for circulating the water from the pump longitudinally through a portion of the engine head and then to the cylinder jackets, a chamber adjacent the engine head, means for conducting the water from the cylinder jackets to the said chamber, and a thermostat for controlling the flow of water from the said chamber to the said pump.

8. The combination with an internal combustion engine, of a cooling system therefor including, a pump mounted on the head of the engine, an intake manifold formed in said head to secure the water discharged from said pump, means for conducting the water from said manifold to the cylinder jackets and from the cylinder jackets to the head proper and thence to said pump and thermostatic means controlling the flow of water to said pump.

9. The combination with an internal combustion engine, of a cooling system therefor including, a pump and means for initially circulating the water from the pump through a portion of the engine head and then through the cylinder jackets, baffle means in said cylinder jackets for directing the water across said jackets, and means for conducting the water from said cylinder jackets through said head to said pump.

10. The combination with an internal combustion engine including a cylinder block provided with a plurality of cylinders and a single cylinder head for said block, of a cooling system for the said engine, including a water pump, a water inlet passage extending throughout the length of the said cylinder head and connected to the water pump, and cylinder jackets surrounding the cylinders and connected respectively to the water inlet passage in the head and the said pump, whereby water may be circulated from the pump through the water inlet passage around the said cylinders and back to the said pump.

11. The combination with an internal combustion engine including a cylinder head and a cylinder block, of a cooling system therefor, including a water pump and means dividing said cylinder head into a plurality of longitudinally extending passages constituting water inlet and outlet passages respectively.

12. The combination with an internal combustion engine including a cylinder block and a cylinder head, of a cooling system therefor including a water pump arranged at one end of the said head and a pair of longitudinally extending passages in the head, the outlet side of the pump being connected to one of the said passages and the inlet side of the pump being connected to the other of the said passages.

13. The combination with an internal combustion engine including a cylinder block and a cylinder head, of a cooling system therefor including a water pump, and water passages

for conducting the water from the said pump longitudinally through a portion of the cylinder head, from the said head to cylinder jackets surrounding the cylinders in the block, from the cylinder jackets around the valves and spark plugs respectively and from around the said spark plugs back to the head and to the pump.

14. The combination with an internal combustion engine including a cylinder block and a cylinder head, of a cooling system therefor including a chamber mounted on the said cylinder head, a pump carried by the said chamber, water passages connecting the said pump with the said head and cylinder block respectively, and a thermostat carried by the said chamber for controlling the flow of water to the said pump.

15. The combination with an internal combustion engine having a cylinder head, of a cooling system for said engine including a water pump, a water inlet passage in said head connected to said pump, a cylinder water jacket connected respectively to said water inlet passage and said pump and a thermostat for controlling the flow of water from said cylinder water jacket to said pump.

In testimony whereof I affix my signature.
EARLE S. MACPHERSON.
